(57) **CLAIM**

The ornamental design for clock radio with digital media player receptacle, as shown and described.

DESCRIPTION

FIG. 1 is a top, front, right side, perspective view of a clock radio with digital media player receptacle showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken line showing of the cord, rear connector and plug elements, various top buttons, text and the broken line on the top surface, represent the portions of the design that form no part of the claimed design.

1 Claim, 7 Drawing Sheets
